(57) **CLAIM**

What is claimed is the ornamental design for a stern of a raft, as shown and described.

DESCRIPTION

FIG. 1 is a top, front, and left-side perspective view of a stern of a raft, showing the new design; FIG. 2 is a top view thereof; FIG. 3 is left-side elevational view thereof; FIG. 4 is a right-side elevational view thereof; FIG. 5 is a bottom view thereof; FIG. 6 is a rear elevational view thereof; FIG. 7 is a front elevational view thereof; and, FIG. 8 is a top, rear, and right-side perspective view thereof. The broken lines represent the environment in which the article resides and forms no part of the claimed design.

1 Claim, 7 Drawing Sheets
